ADJUSTABLE BED FRAME

John Maguire, Wichita, Kans., assignor to Duo-Bed Corporation, Los Angeles, Calif., a corporation of Delaware

Filed May 4, 1961, Ser. No. 107,725
6 Claims. (Cl. 5—202)

This invention relates to an adjustable bed frame.

It is an object of my invention to provide a bed frame which is adapted to be easily and quickly assembled by a completely unskilled person without the use of any tools whatsoever and without the use of any conventional fastening members such as nuts, screws, bolts and the like. My bed frame structure is so simple that it is capable of being assembled or adjusted in the home by the ordinary home owner or housewife without any assistance whatsoever.

It is a further object of my invention to provide such a bed frame which is adjustable in size, with such adjustments also capable of being made without the use of tools or conventional fastening members.

Another object of my invention is to provide such a bed frame which is capable of being collapsed to a compact knocked-down form for easy shipment and handling.

A more particular object of my invention is to provide an improved adjustable bed frame in which the transversely extending cross members of the frame are telescopically connected to each other and in which they are locked into fixed relationship with each other through the use of a spring member having a cam action for providing sufficient frictional engagement between the telescoping frame members.

It is accordingly an object of my invention to provide an adjustable bed frame having all of the benefits and advantages of the structure set forth above and described in detail hereinafter in this specification. My invention also comprises such other objects, advantages and capabilities as will later more fully appear and which are inherently possessed by my invention.

While I have shown in the accompanying drawings a preferred embodiment of my invention, it should be understood that the same is susceptible of modification and change without departing from the spirit of my invention.

Referring to the drawings,

FIG. 1 is a top plan view of a complete bed frame in assembled condition;

FIG. 2 is an enlarged view of one corner, showing the attachment of a cross member to the side rail and the attachment of a roller to the cross member;

FIG. 3 is a sectional view of the same, taken on line 3—3 of FIG. 2;

FIG. 4 is a top plan view of one of the side rails with the attached cross members in collapsed or knocked-down position;

FIG. 5 is an enlarged bottom plan view, partly broken away, showing the cam spring connection between the cross members;

FIG. 6 is a longitudinal sectional view of the same, taken on line 6—6 of FIG. 5.

A preferred embodiment which has been selected to illustrate my invention comprises a bed frame 10 having a pair of side rails 11, which may be formed of angle iron in the conventional manner. Each of the side rails 11 thus comprises a side wall 12 and a bottom wall 13. The head of the frame 10 is provided with a pair of brackets 14 for attaching a headboard 15.

A pair of large channel cross members 16 are pivotally attached at one end thereof to one of the side rails 11 by pivot pins or rivets 17 which extend through the bottom walls 13 of the side rails 11. A pair of complemen-

2

tarily formed small channel cross members 18 are pivotally attached at one end thereof to the other side rail 11 in positions opposite the large channel members 16 by similar pivot pins or rivets 19.

5 A plurality of rollers 20 are mounted beneath the cross members 16 and 18 for moving the frame. While elongated rollers 20 are shown, any suitable rollers or conventional casters may be used.

When the frame 10 is in collapsed or knocked-down condition, the cross members 16 and 18 are pivoted into positions in which they lie closely adjacent to and almost parallel with the side rails 11, as shown in FIG. 4 of the drawings.

10 In order to assemble the frame for use, the cross members 16 and 18 are pivoted outwardly away from the side rails 11. Each of the side rails 11 is provided along the bottom wall 13 thereof with a pair of stop members 21, which may be punched or deformed downwardly beneath the bottom wall 13 adjacent to the rivets 17 and 19.

15 20 When the cross members 16 and 18 are pivoted into a position in which they extend perpendicular to the side rails 11, they engage the stop members 21, which prevent their further pivotal movement. The stop members 21 thus act as guides for the proper positioning of the cross members 16 and 18.

25 Each of the cross members 16 and 18 is channel-shaped in cross section. The large cross member 16 includes a top wall 22, a pair of side walls 23 and a pair of inwardly directed partial bottom walls 24, which extend only a short distance inwardly from the side walls 23, the remainder of the bottom of the cross member 16 being open. The small cross member 18 similarly includes a top wall 25, a pair of side walls 26 and a pair of inwardly directed partial bottom walls 27.

30 35 The small cross members 18 are dimensioned to fit slidably and telescopically within the larger cross members 16, when inserted into the open ends thereof remote from the side rails 11. The cross members 16 and 18 are then telescoped together to provide the desired width of bed frame. In order to lock the cross members 16 and 18 together and prevent their further movement with respect to each other, a cam lock is provided which is simple to use and capable of quick manual operation without requiring any tools.

40 45 An axle pin 30 extends transversely across each of the small cross members 18 adjacent the end thereof remote from the side rail 11. A cam spring 31 is provided at one end with a plurality of coils 32, which extend around the axle pin 30. Adjacent the center of the cross member 18 is an end coil 33 of gradually increased diameter. The portion of the end coil 33 which is disposed toward the top wall 25 of the cross member 18 and which is of substantially greater diameter than the coils 32 is provided with a plurality of spaced serrations 34. Extending longitudinally along the cross member 18 from the end coil 33 is a straight portion 35, which terminates in a loop 36. The loop 36 extends laterally toward one side wall 26 of the cross member 18 beyond the inner edge of the adjacent partial bottom wall 27.

50 55 60 The center of the top wall 25 of the cross member 18 is provided with an elongated longitudinally directed slot 37, which is disposed directly adjacent to the end coil 33 of the cam spring 31.

65 The cam spring 31 is adapted to be manually moved between two positions, in one of which it is unlocked or released and in the other of which it is locked or engaged to prevent movement of the cross members 16 and 18 with respect to each other.

70 75 The cam spring 31 is shown in its locked position in FIGS. 5 and 6 of the drawings. In such position, the serrated portion of the end coil 33 extends completely through

the slot 37 so that its serrations 34 engage the top wall 22 of the large cross member 16 to prevent any longitudinal movement of the cross members 16 and 18 with respect to each other. The cam spring 31 is held in its locked position by the loop 36, which resiliently fits and is held beneath the partial bottom wall 27 of the cross member 18.

The cam spring 31 may be released by moving the loop 36 and straight portion 35 laterally against the inherent resilience of the cam spring 31 until the loop 36 is out from beneath the partial bottom wall 27 of the cross member 18. The loop 36 and straight portion 35 are then free to be rotated by the resilience of the cam spring 31 in a downward or clockwise direction. Rotation of the loop 36 and straight portion 35 causes the diametrically enlarged portion of the end coil 33 which carries the serrations 34 to be rotatably disengaged from the top wall 22 of the large cross member 16 as a portion of the end coil 33 having a smaller diameter is brought into alignment with the slot 37. This diametrically smaller portion of the end coil 33 does not reach completely through the slot 37 and accordingly does not engage the top wall 22 of the large cross member 16.

The cam spring 31 may be returned to its locked position by rotating the loop 36 and straight portion 35 in a counter-clockwise direction to move the serrations 34 of the end coil 33 through the slot 37 into engagement with the top wall 22 of the large cross member 16. The loop 36 is moved laterally to pass it around and beneath the partial bottom wall 27 beneath which it is held by the resilience of the cam spring 31.

I claim:

1. In an adjustable bed frame having a pair of telescopically mounted cross members movable longitudinally with respect to each other to adjust the width of said bed frame, means for locking said cross members against such longitudinal movement, said means comprising an axle extending transversely across the inner cross member, a cam spring having at one end thereof a plurality of coils extending around said axle, said cam spring having an end coil, said end coil having a diameter gradually increasing to a diameter substantially greater than that of the remainder of said coils, said end coil being disposed adjacent the center of said inner cross member, said inner cross member having a centrally disposed longitudinally directed slot disposed adjacent to said end coil, the diametrically increased portion of said end coil being dimensioned to extend through said slot and engage the outer cross member, said portion having a plurality of serrations adapted to increase the frictional engagement between said end coil and said outer cross member, said cam spring having a straight portion extending substantially radially from said end coil, said cam spring being movable between two positions, in one of which the serrated portion of said end coil extends through said slot and frictionally engages said outer cross member to lock said cross members against movement, and in the other of which said cam spring is rotated to move the serrated portion of said end coil out of engagement with said outer cross member to permit longitudinal movement of said cross members with respect to each other.

2. The structure described in claim 1, the straight portion of said cam spring having a loop at the end thereof remote from said end coil, said loop extending laterally toward one side of said inner cross member, said inner cross member having a partially closed wall, said loop being adapted to fit within said inner cross member and to be normally held therein by said wall, said cam spring when in locked position being disposed entirely within said cross member and being held therein by said wall, said loop and straight portion adapted to be moved laterally around said wall to permit the movement of said loop to and from said position within said inner cross member as said cam spring is moved between said positions.

3. In an adjustable bed frame having a pair of telescopically mounted cross members movable longitudinally

5 with respect to each other to adjust the width of said bed frame, means for locking said cross members against such movement, said means comprising a cam spring mounted on the inner cross member, said cam spring having a coil of gradually increasing diameter, said inner cross member having a slot disposed adjacent to said coil, the diametrically increased portion of said coil being dimensioned to extend through said slot and engage the outer cross member, said portion having a plurality of serrations adapted to increase the frictional engagement between said coil and said outer cross member, said cam spring being movable between two positions, in one of which the serrated portion of said coil extends through said slot and frictionally engages said outer cross member to lock said cross members against movement, and in the other of which said cam spring is rotated to move the serrated portion of said coil out of engagement with said outer cross member to permit longitudinal movement of said cross members with respect to each other.

4. In an adjustable bed frame having a pair of telescopically mounted cross members movable longitudinally with respect to each other to adjust the width of said bed frame, means for locking said cross members against such movement, said means comprising a cam spring mounted on the inner cross member, said cam spring having a coil of increased diameter, said inner cross member having a slot disposed adjacent to said coil, the diametrically increased portion of said coil being dimensioned to extend through said slot and engage the outer cross member, said cam spring being movable between two positions, in one of which the diametrically increased portion of said coil extends through said slot and frictionally engages said outer cross member to lock said cross members against movement, and in the other of which said cam spring is rotated to move the serrated portion of said coil out of engagement with said outer cross member to permit longitudinal movement of said cross members with respect to each other.

5. In an adjustable bed frame having a pair of telescopically mounted cross members movable longitudinally with respect to each other to adjust the width of said bed frame, means for locking said cross members against such longitudinal movement, said means comprising a cam spring having at one end an end coil, said end coil having a diameter greater than that of the remainder of said coils, said inner cross member having a longitudinally directed slot disposed adjacent to said end coil, the diametrically increased portion of said end coil being dimensioned to extend through said slot and engage the outer cross member, said portion having a plurality of serrations adapted to increase the frictional engagement between said end coil and said outer cross member, said cam spring having a straight portion extending substantially radially from said end coil, said cam spring being movable between two positions, in one of which the serrated portion of said end coil extends through said slot and frictionally engages said outer cross member to lock said cross members against movement, and in the other of which said cam spring is rotated to move the serrated portion of said end coil out of engagement with said outer cross member to permit longitudinal movement of said cross members with respect to each other.

6. In an adjustable bed frame having a pair of telescopically mounted cross members movable longitudinally with respect to each other to adjust the width of said bed frame, means for locking said cross members against such movement, said means comprising a cam spring mounted on the inner cross member, said inner cross member having a slot disposed adjacent to said cam spring, said cam spring having an enlarged portion dimensioned to extend through said slot and engage the outer cross member, said cam spring being movable between two positions, in one of which said enlarged portion of said cam spring extends through said slot and frictionally engages said outer cross member to lock

said cross members against movement, and in the other of which cam spring is rotated to move said enlarged portion out of engagement with said outer cross member to permit longitudinal movement of said cross members with respect to each other.
